CLOTHESBRUSH OR THE LIKE

Clyde A. Porter, Aurora, Ill., assignor to National Brush Company, Aurora, Ill., a corporation of Illinois

Application March 3, 1952, Serial No. 18,756

Term of patent 7 years

(Cl. D9—2)

To all whom it may concern:

Be it known that I, Clyde A. Porter, a citizen of the United States, residing in the city of Aurora, county of Kane, State of Illinois, have invented a new, original, and ornamental Design for a clothes Brush or the like, of which the following is a specification, reference being had to the accompanying drawing, forming a part thereof, in which:

Figure 1 is a perspective view of the clothes brush or the like, showing my new design;

Fig. 2 is a top plan view thereof;

Fig. 3 is a side elevational view;

Fig. 4 is a sectional view along the line 4—4 of Fig. 3, showing the detail of the design configuration at that point; and

Fig. 5 is a cross sectional view along the line 5—5 of Fig. 3, showing the design configuration of the handle of the brush at the point indicated.

I claim:

The ornamental design for a clothes brush or the like, substantially as shown.

CLYDE A. PORTER.
